BEVELING DEVICE

Edward Almer Hermanson, Santa Monica, Calif.

Application November 19, 1947, Serial No. 786,978

5 Claims. (Cl. 90—15)

1

My invention relates to beveling devices and more particularly to a beveling device especially adapted to bevel the end edge surfaces of bars forming frames used for the purpose of holding together the set type of advertisements and short items prepared in printing offices. It is, however, to be understood that the beveling device according to my invention may be used also for beveling the end surfaces of abutting members of frames used for other purposes.

The object of my invention is to provide a beveling device of the character indicated above, which is adapted, in addition to the beveling of the abutting end surfaces of adjoining frame members, to form interlocking dovetail grooves and dovetail tenons on said abutting end surfaces, so that the bars forming small compositor frames may be securely held together.

Other objects of my invention not specifically mentioned may appear in the following specification describing my invention with reference to the accompanying drawing illustrating a preferred embodiment of my invention. It is, however, to be understood, that my invention is not to be limited or restricted to the exact construction and combination of parts described in the specification and shown in the drawing, but that such changes and modifications can be made, which fall within the scope of the claims appended hereto.

In the several figures of the drawing illustrating my invention similar parts are designated by similar reference characters, and

Figure 1 is an elevational side view of the beveling device according to my invention.

Figure 2 is an elevational right hand end view of Figure 1.

Figure 3 is a sectional view taken on line 3—3 in Figure 1.

Figure 4 is a sectional view taken on line 4—4 in Figure 1.

Figure 5 is a detail view of the motor and the beveling mechanism partly shown in elevation and partly in section.

Figure 6 is a sectional view taken on line 6—6 in Figure 5.

Figure 7 is a fragmentary perspective view of a frame member provided with a beveled end surface on which a dovetail tenon is formed, and

Figure 8 is a fragmentary perspective view of a frame member provided with a beveled end surface, in which a dovetail groove is cut.

The beveling device forming the subject matter of my invention comprises a track-member 10 of substantially rectangular cross section, one

2

end portion 11 of which is reduced in thickness and forms the base of a milling mechanism M to be described later. At an equal distance below the top surface of the track-member 10 a longitudinal dovetail groove 12 is arranged in each longitudinal side of said member and runs parallel to the top surface of the track member. A clamp 13 is shaped substantially like an inverted U and the flanges 13a of said clamp fit slidably on the longitudinal sides of the track-member 10. On the inside surface of each clamp flange 13a, a dovetail tenon 14 is formed adapted to engage slidably the corresponding dovetail groove 12. In the inside surface of the web 13b of the clamp 13, a comparatively wide and shallow rectangular groove 15 is formed, adapted to receive a flat frame member 16 therein. Centrally of the web 13b of the clamp 13, a tapped hole 17 is located and a thumb screw 18 engages said tapped hole and is adapted to secure the flat frame member 16 in adjusted position.

A small electric motor 19 or the like forms a part of the mechanism M and is mounted on the outer end of the base 11 of said mechanism.

25 A housing 20 having a rectangular cross section is mounted on the base 11 intermediate the track 10 and the motor 19. The motor shaft 21 extends through the rear end wall 20a of the housing on the vertical center line thereof and is ro-

30 tatably supported by a bearing 22 secured on the inside surface of said wall. On the end of the motor shaft 21, a universal joint 23 is rigidly mounted and a milling spindle 24 is secured to the other end of the universal joint by means of

35 a square shaft portion 25. The milling spindle 24 extends through a vertical slot 26 provided in the front end wall 20b and a milling cutter c is removably secured to the front end of the spindle. The milling cutter is formed with a milling face

40 27 and a milling circumferential surface 28, which extends rearwardly from the face at an angle of 45°.

A pulley 29 is rigidly mounted on the motor shaft 21 between the motor 19 and the housing 20, and two stub shafts 30 extend through the rear wall 20a of the housing 20 and are rotatably mounted in bearings 31 arranged on the inner surface of the rear housing wall at an equal distance from the vertical center line of said wall

50 and at a higher level than the first mentioned bearing 22. On the outer end of each stub shaft 30, a pulley 32 is rigidly mounted and an endless belt 33 is trained over the three pulleys 29 and 32. Inside the housing 20 a universal joint 34 is secured to the end of each stub shaft 30 and

a milling spindle 35 is attached to each universal joint and extends through a vertical slot 36 in the front end wall 20b. Outside of the housing 20 another milling cutter c is removably secured onto the end of each milling spindle 35. These milling cutters are formed identically with the first milling cutter c.

On the base end portion 11 of the track-member 10, an upwardly extending bracket 37 is mounted inside the housing 20 and supports a crank lever L pivotally on a pivot pin 38 extending horizontally through said bracket. One arm 39 of said crank lever extends slantingly upward and the other arm 40 extends through a vertical slot 41 in a side wall of the housing 20. The upwardly extending lever arm 39 is provided with a longitudinal slot 42. A sleeve 43 surrounds slidably the first mentioned milling spindle and has a downwardly extending lever arm 44 which is connected with the upward lever arm 39 by means of a pivot pin 45 secured in the lever arm 44 and located slidably in the slot 42 in the upwardly slanting lever arm 39. Normally the milling spindle 24 swings downwardly on the universal joint 23 by gravitation into the position indicated in Figure 5 in broken lines, thereby urging the outwardly extending lever arm 40 upwardly. By forcing this lever arm down, the milling spindle is pivoted upwardly in the position shown in full lines in Figure 5 for a purpose to be described later.

Each upper milling spindle 35 is surrounded slidably by a sleeve 46 located inside the housing 20 and these two sleeves are connected with each other by means of a bar 47 or the like provided with a downwardly extending arm 48. A connecting bar 49 is pivotally connected at its upper end with the arm 48, as at 50 in Figure 5, and has a pivot pin 51 in its lower end portion. This pin extends through a vertical slot 52 in the side wall of the housing, in which the slot 41 is arranged. Vertically underneath of the slot 52, two guide rings 53 are secured to said housing wall at a distance from said slot and from each other. An adjusting rod 54 is located slidably in the two guide rings 53 and the pivot pin 51 extends pivotally diametrically through the upper end portion of said adjusting rod. Directly underneath the guide rings 53 a small guide bracket 55 projects from the base portion 11 of the track-member 10 and a bore 56 extends coaxially with the guide rings 53 through said guide bracket and the lower end portion of the adjusting rod is located slidably in said bore. A helical spring 57 surrounds the portion of the adjusting rod underneath the lower guide ring 53 and abuts with its lower end a washer 58 resting on the guide bracket 55, and with its upper end a pin 59 extending diametrically through the adjusting rod 54 under the lower guide ring, normally urging the adjusting rod upwardly, so that the two milling spindles 35 will be normally located in the position shown in full lines in Figure 5. A hand grip 60 is secured to the adjusting rod 54 between the two guide rings 53, and by forcing the hand grip down the two milling spindles 35 and the cutters c secured thereon are pivoted down into the position shown in broken lines in Figure 5. Upon release of the hand grip the spring 57 returns the spindles and cutters into normal position.

The above described device operates as follows:

A flat piece 16 of metal is placed on the track-member 10 and adjusted to extend a certain

length beyond the track and over the base 11. The clamp 13 holds the flat bar 16 in adjusted position. The motor 19 is started, and the handgrip 60 is forced down, so that the two spindles 35 and the milling cutters c on said spindles are pivoted downwardly into working position shown in broken lines in Figure 5. The milling cutters engage the metal bar 16 with the milling surfaces 28 so that the bar end portions 61 adjacent to the longitudinal edges of said bar are beveled at an angle of 45°. Then the handgrip is released and the milling spindles 35 with their milling cutters are returned to idle position as shown in full lines in Figure 5. The clamp 13 is released and the flat metal bar is adjusted in desired position, and the crank lever L is actuated to lift the milling spindle 24 into horizontal working position shown in full lines in Figure 5, so that the flat milling face 27 of the milling cutter secured to the spindle 25 will face the bar end surface portion 62 left between the two beveled portions 61. This portion 62 has beveled side surfaces 63, forming a dovetail tenon 62 because the two milling surfaces 28 and 29 of each milling cutter extend to each other at an angle of 45°. Both ends of a flat bar 16 are finished in this manner, and then the ends of another bar 16 are finished as follows:

The bar 16 is adjusted on the track-member 10 and secured in position. The bar end portions adjacent the longitudinal edges of said bar are beveled by means of the two milling cutters c on the milling spindles 35, as described above. The bar 16 is adjusted again, so that the milling cutter on the milling spindle 24 will cut a dovetail groove 64 into the bar end between the beveled end portions 61 when it is arranged in working position. The dovetail tenon 62 fits snugly into the dovetail groove 64.

Two bars 16 are provided with dovetail tenons 62 at each end and two other bars with dovetail grooves 64 and the bar end portions adjacent to said tenons and grooves are beveled, so that these bars can be easily assembled to form a frame.

The housing 20 is closed by a cap 65 fitting into the housing and resting on the upper edges of the housing walls.

I claim:

1. A device for beveling the ends of bars designed to form compositor frames or the like including an elongated track member adapted to support a frame bar, a milling mechanism mounted at one end of said track member, means for securing said frame bar on the track member so that it extends a selected predetermined distance beyond the said track end, the milling mechanism comprising a motor, a motor shaft, a universal joint on said shaft, a milling spindle, a milling cutter removably secured on said milling spindle, said spindle being adapted to pivot downwardly by gravitation into idle position, and means for lifting said spindle into horizontal working position, said means consisting of a sleeve rotatably mounted on the spindle, a downwardly extending arm formed on the sleeve, a pivot pin on the arm adjacent to its end, and a crank lever pivotally mounted at the track end, one arm of said lever extending slantingly upward and provided with a longitudinal slot, in which the pivot is slidably located and the other lever arm extending rearwardly, so that the spindle may be pivoted upwardly into horizontal working position by pushing the second lever arm down.

2. A device for beveling the ends of bars designed to form compositor frames or the like including an elongated track member adapted to support a frame bar, a milling mechanism mounted at one end of said track member, means for securing said frame bar on the track member so that it extends a selected predetermined distance beyond the said track end, the milling mechanism comprising a motor, a motor shaft, a pulley on said shaft, a housing mounted in front of the motor, two stub shafts rotatably supported in the rear wall of the housing and located at a higher level than the motor shaft, a pulley rigidly mounted on the outer end portion of each stub shaft, an endless belt trained over the three pulleys, a universal joint inside the housing on the end of each stub shaft, a milling spindle connected with each universal joint and extending through a vertical slot in the front wall of the housing, a milling cutter removably mounted on the free end of each milling spindle, and means for holding the spindles and cutters normally in upward idle position.

3. A device for beveling the ends of bars designed to form compositor frames or the like including an elongated track member adapted to support a frame bar, a milling mechanism mounted at one end of said track member, means for securing said frame bar on the track member so that it extends a selected predetermined distance beyond the said track end, the milling mechanism comprising a motor, a motor shaft, a pulley on said shaft, a housing mounted in front of the motor, two stub shafts rotatably supported in the rear wall of the housing and located at a higher level than the motor shaft, a pulley rigidly mounted on the outer end portion of each stub shaft, an endless belt trained over the three pulleys, a universal joint inside the housing on the end of each stub shaft, a milling spindle connected with each universal joint and extending through a vertical slot in the front wall of the housing, a milling cutter removably mounted on the free end of each milling spindle, means for holding the spindles and cutters normally in upward idle position, said means comprising a bar or the like connecting the spindles, an arm on said bar, a connecting bar pivotally mounted with one of its end portions onto the arm, a pivot pin extending

through the other end portion of the connecting bar, through a vertical slot in the rear housing wall and extending diametrically through an adjusting rod slidably arranged in guide rings mounted above each other on the outside of said rear wall, a spring adapted to urge the adjusting rod upwardly to pivot the spindles and cutters into idle position, and a hand grip or the like secured on the adjusting rod to facilitate the imparting of downward sliding movement to said rod.

4. A device for beveling and forming dovetail elements on the ends of bars designed to form compositor frames or the like, comprising a work bed for supporting a frame bar, a milling cutter, a spindle carrying the cutter and pivotally supported at one end to be vertically swung to a position in which its turning axis is substantially in line with the end of a bar on the bed, means for swinging the cutter vertically into and out of said position, a pair of milling cutters, spindles supporting the latter for vertical swinging movement across the said end of the bar in vertical planes passing on the two sides of the swinging plane for the first spindle, means for swinging the pair of spindles, and means for rotating the cutters.

5. A device as set forth in claim 4 in which each milling cutter is of conical form and joined at its apex to the end of its supporting spindle, and the pair of cutters being supported above the work bed and swinging about a center located at substantial height above the swinging center for the first cutter.
